UNITED STATES PATENT OFFICE.

HERON R. PALMER, OF ERIE, PENNSYLVANIA.

DESIGN FOR A BICYCLE HANDLE-BAR GRIP.

60,702.

Specification for Design.

Patented Mar. 21, 1922.

Application filed July 10, 1920. Serial No. 395,395. Term of patent 7 years.

To all whom it may concern:

Be it known that I, HERON R. PALMER, a citizen of the United States, residing at Erie, in the county of Erie and State of Pennsylvania, have invented a new, original, and ornamental Design for a Grip, particularly a Bicycle Handle-Bar Grip, of which the following is a specification, reference being had to the accompanying drawing, forming part thereof.

The figure is a plan view of a bicycle handle-bar grip, showing my new design.

I claim:

The ornamental design for a bicycle handle-bar grip, as shown.

HERON R. PALMER,

Witnesses:

C. C. STRICKLAND,
A. Y. CALDWELL.
